UNITED STATES PATENT OFFICE.

OTTO E. MAUL, OF MOUNT VERNON, NEW YORK, ASSIGNOR TO CHRISTIAN E. HERTLEIN, OF NEW YORK, N. Y.

DESIGN FOR A ROSETTE.

41,156.

Specification for Design.

Patented Feb. 7, 1911.

Application filed November 26, 1910. Serial No. 594,415. Term of patent 7 years.

To all whom it may concern:

Be it known that I, OTTO E. MAUL, a citizen of the United States of America, residing at Mount Vernon, in the county of Westchester and State of New York, have invented a new, original, and ornamental Design for Rosettes, of which the following is a specification, reference being had to the accompanying drawing, forming part thereof.

The figure is a plan view of the rosette showing my new design.

I claim:

The ornamental design, for a rosette as shown.

OTTO E. MAUL.
